H. A. RAGLE,
INDICATING DEVICE FOR MOVING PICTURES,
APPLICATION FILED MAR. 25, 1919.

Patented Mar. 2, 1920.

FIG. 1.

Inventor
Henry A. Ragle

By

Asst. Atty.

Attorney

UNITED STATES PATENT OFFICE.

HENRY A. RAGLE, OF MARYVILLE, TENNESSEE.

INDICATING DEVICE FOR MOVING PICTURES.

1,332,869.

Specification of Letters Patent.

Patented Mar. 2, 1920.

Application filed March 25, 1919. Serial No. 284,977.

To all whom it may concern:

Be it known that I, HENRY A. RAGLE, a citizen of the United States, residing at Maryville, in the county of Blount and State 5 of Tennessee, have invented certain new and useful Improvements in Indicating Devices for Moving Pictures, of which the following is a specification, reference being had thereto in the accompanying drawing.

10 This invention relates to indicating devices for moving pictures, the object being to provide an indicating device by means of which the public will be kept informed as to the reel being shown within the theater.

15 Another object of my invention is to provide an indicating device in the form of a removable dial adapted to be placed on a clock, such dial being provided with spaces to receive the title of the show or the photograph of the featuring star.

20 Another and further object of the invention is to provide an indicating device in the form of a dial which can be used for advertising purposes, the dial being practically formed of paper to enable the same to be manufactured very cheaply and by printing on the dial the shows which will be displayed in the theater for a week or a day, a person can readily place one of these dials on a 25 clock so that he will be able to ascertain just what reel is being displayed at any particular time of the day.

25 In the drawing, I have shown a face view of a clock in which A indicates the clock which is provided with the usual hour and minute hands B and C and over which is arranged a dial D which is split at D' in order to allow the same to be readily placed in position on the clock. The dial is provided 30 with numerals from one to twelve, indicating the hours of the day and the spaces between these numerals are subdivided by dashes E into twelve minute periods, representing the time ordinarily required to display 35 one reel.

40 The dial is subdivided into spaces F which are determined by the number of reels being displayed in any one feature. These spaces corresponding with the period spaces and 45 with the hour hands in such a manner that when the dial is placed in position upon a clock and the first reel is to be displayed at a given time, a person will be able to determine just what reel is being shown within 50 the theater by examining the clock so that if there is any particular feature being shown in the theater he will be able to ar-

range to see this particular feature without having to wait the display of other features. The face is also divided into spaces 60 G and the spaces f and G are adapted to receive either the photograph of the star featuring in the particular reel or to have printed therein the title of the reel.

55 By subdividing the dial into spaces in this manner, a clock provided with one of these indicating devices will indicate the reel being displayed at any time of the day. By using these dials for advertising purposes, they can be readily placed on the clock which 70 will allow a person to decide and make his arrangements to see any particular reel without wasting the time of waiting for a particular reel to be displayed. In the drawing I have shown a dial adapted in the particular 75 manner but I do not wish to limit myself to the subdivisions in the dial as this will be determined by the number of reels in any one feature as the main object of my invention is to provide an indicating device by 80 means of which a person on the outside of a theater can ascertain just what reel is being displayed at any time of the day.

I do not wish to limit myself to any particular use of the dial as the same could be 85 used for advertising purposes and could be printed in newspapers and periodicals as an advertising medium and could be used in connection with a dummy clock without departing from the spirit of my invention. 90

What I claim is:—

1. An indicating device for moving pictures comprising a dial split radially to allow it to be placed over the face of a clock having numerals from one to twelve designating the hours of the day and subdivisions 95 designating the time required to display a reel.

2. A device of the kind described comprising a dial split to allow it to be placed on a clock, said dial having numerals from one to twelve indicating the hours of the day and spaces between the hours of the day indicating the time required to display one reel, said dial having spaced to receive the photograph of the feature of the reel or the title of the reel whereby the reel being displayed at any particular time will be indicated. 100

105 In testimony whereof I hereunto affix my signature in the presence of two witnesses. 110
